US00D899946S

(12) **United States Design Patent** (10) **Patent No.:** **US D899,946 S**
(45) **Date of Patent:** **** Oct. 27, 2020**

(54) **MEASURING INSTRUMENT**

- (71) Applicant: **E+E ELEKTRONIK Ges.m.b.H,**
Engelwitzdorf (AT)
- (72) Inventor: **Stefan Polly**, Unterweissenbach (AT)
- (73) Assignee: **E+E ELEKTRONIK Ges.m.b.H** (AT)
- (**) Term: **15 Years**
- (21) Appl. No.: **29/676,392**
- (22) Filed: **Jan. 10, 2019**

(30) **Foreign Application Priority Data**

- Jul. 24, 2018 (EM) 005511623-0001
